UNITED STATES PATENT OFFICE.

OTTO KUNERT, OF BRESLAU, GERMANY.

CIRCULATING DEVICE.

Application filed August 9, 1920. Serial No. 402,483.

(GRANTED UNDER THE PROVISIONS OF THE ACT OF MARCH 3, 1921, 41 STAT. L., 1313.)

To all whom it may concern:

Be it known that I, OTTO KUNERT, a citizen of the German Republic, residing at Breslau, Germany, have invented certain new and useful Improvements in Circulating Devices (for which I have filed application in Germany, Aug. 3, 1916, Patent No. 309,459), of which the following is a specification.

10 This invention relates to improvements in water circulating devices as described in my U. S. A. Patent No. 829970 of 4th of September 1906 and it consists in arranging in the steam chamber of water circulating devices of this type, besides the outlet-nozzles which serve for the production of the water circulation and which are situated under the water level, other outlet-nozzles for the steam terminating upon the surface of the water and designed to produce a surface current in the water designed to remove the oil containing sediments which float upon the surface of the water. Part of the steam which collects in the steam chamber of the water circulating device is thus utilized for the production of the water circulation in the known manner, another part of this steam being utilized for the production of the surface current.

20 In the accompanying drawings the invention is shown in combination with a water circulator.

Figs. 1 to 3 show the first form of construction in longitudinal section, in cross section and in plan view respectively.

Fig. 4 represents a constructional detail.

Fig. 5 is a longitudinal section of the second form of construction.

Fig. 6 is a longitudinal section of the third form of construction.

In all the forms of execution which are shown, *f* designates the boiler flue tube, *s* the steam catching hood of the water circulator, *h* the steam collector proper, *w* the baffling plates, *a* and *a'* the exhaust connecting branches of the steam collector, *n* the water level.

According to the invention the steam jet producer *o* is connected with the water circulator *h*, which is constructed in the well known manner. The device for removing the floating sediments consists of a steam tube *r* upwardly directed and of a trough *d* without front wall which is turned upside

down and arranged at the height of the water level. This trough *d* is fan-shaped in plan view. The side walls of the trough are designated by *u*, lateral partitions *e* of the trough serve to divide the steam which is admitted to the trough into steam jets of different directions.

As shown in Fig. 1 the steam tube *r* is rigidly connected with the steam collecting hood *h* and mounted in the front wall of the same between the exhaust connecting branches *a* and *a'* (Fig. 3) so that it communicates with the steam outlet opening *b*.

As shown in Fig. 5 the position of the trough *d* upon the vertical tube *r* which traverses the top plate of the steam collecting hood *h* can be regulated according to the height of the water level *n*.

The form of construction shown in Fig. 6 differs from the forms of construction hereinbefore described in so far that the position of the trough *d*, connected with the steam tube *r*, is automatically adjusted with regard to the height of the water level in the boiler. With this object in view the trough is made floatable owing to hollow spaces or it is provided with a counter-weight *g* floating upon the water so that the water pressure and the steam pressure maintain the trough *d* continually at the proper height. The up and down movement of said trough is very favorable for the result to be attained.

In all forms of construction the effect aimed at is attained through steam jets flowing out from the trough *d* in various directions, the steam being conducted into said trough by means of the tube *r*. The steam jets flow out of the trough horizontally so that they pass over the surface of the water and remove the layer of greasy sediments.

I claim:-

1. In a steam-boiler the combination with a flue of a baffle forming a chamber partially surrounding said flue, a cap forming a steam chamber in communication with said chamber formed by the baffle and divided into a number of compartments and outlet-nozzles in communication with said cap and adapted to discharge in the longitudinal direction of the boiler said nozzles being partially open below, some of said outlet-nozzles being situated below the surface of the water and some of said outlet-

- nozzles being situated upon the surface of the water.
2. In a steam-boiler the combination with a flue of a baffle forming a chamber partially surrounding said flue, a cap in communication with said chamber and divided into a number of compartments and outlet-nozzles in communication with said cap and adapted to discharge in the longitudinal direction of the boiler, said nozzles being partly open below and having an upwardly-inclined direction, some of said outlet-nozzles being situated below the surface of the water and some of said outlet-nozzles being situated upon the surface of the water. 45
3. In a steam-boiler the combination with a flue of a baffle forming a chamber partially surrounding said flue, a cap in communication with said chamber and divided into a number of compartments and outlet-nozzles in communication with said cap and adapted to discharge in the longitudinal direction of the boiler said nozzles being partly open below and having an upwardly-inclined and laterally-diverging direction, some of said outlet-nozzles being situated below the surface of the water and some of said outlet-nozzles being situated upon the surface of the water. 50
4. In a steam-boiler the combination with a flue of a baffle forming a chamber partially surrounding said flue, a cap in communication with said chamber and divided into a number of compartments and outlet-nozzles in communication with said cap and adapted to discharge in the longitudinal direction of the boiler said nozzles being partly open below and having an upwardly-inclined and laterally-diverging direction, some of said outlet-nozzles being situated below the surface of the water and some of said outlet-nozzles being situated upon the surface of the water. 55

In testimony whereof I affix my signature in presence of two witnesses.

OTTO KUNERT.
